ATTORNEY

UNITED STATES PATENT OFFICE.

EDWIN F. ALLBRIGHT, OF WOLLASTON, MASSACHUSETTS, ASSIGNOR, BY MESNE ASSIGNMENTS, TO GRID FLAT SLAB CORPORATION, OF BOSTON, MASSACHUSETTS, A CORPORATION OF MASSACHUSETTS.

CONCRETE CONSTRUCTION.

Application filed September 6, 1919. Serial No. 322,182.

To all whom it may concern:

Be it known that I, EDWIN F. ALLBRIGHT, a citizen of the United States, residing at Wollaston, in the county of Norfolk and 5 State of Massachusetts, have invented an Improvement in Concrete Construction, of which the following description, in connection with the accompanying drawings, is a specification, like characters on the drawings 10 representing like parts.

The invention to be hereinafter described relates to concrete construction, and more particularly to continuous flat slabs such as shown, described and claimed in Letters 15 Patent No. 1,307,081, granted June 17, 1919. The flat slab of said patent comprises solid panels resting on columns and projecting substantial distances beyond said columns with cantilever effect, the bays between the 20 solid panels being provided with transversely extending ribs depending therefrom with domes or recesses between said ribs. To support the slab, columns of concrete are provided having flaring capitals beneath and 25 supporting the solid panels.

This is a good, efficient form of construction for many purposes, but in some constructions it is desirable to eliminate the flaring capitals of the columns, and it is desirable to use columns of smaller transverse 30 section than where concrete columns are employed. For example, in office buildings where a floor is divided into a number of rooms by partitions, it may be desirable to 35 have the columns located within the partitions or at the corners or junctures of meeting walls, so that the columns and capitals will not be visible in the rooms.

One of the purposes of the present invention, therefore, is to provide a metal column 40 and a cap therefor appropriate to support a flat slab of the type described above, in which the metal cap may be enclosed within and concealed by the solid panel of the slab, but yet serve efficiently to support the slab.

Where a structure having a number of floors is to be erected, it is customary for the 45 columns to extend up from floor to floor. Another purpose of the invention is to provide a cap which may be formed of sections which may be laterally presented to and secured to the column at any desired point along the length thereof.

With the aforesaid and other objects in view, the character of the invention will be best understood by reference to the following description of one good form thereof shown in the accompanying drawing, wherein:

Fig. 1 is a plan of a portion of a flat slab provided with columns and caps embodying the invention for supporting the slab;

Fig. 2 on an enlarged scale is a vertical section on line 2—2 of Fig. 1;

Fig. 3 is a horizontal section taken on line 3—3 of Fig. 2 showing one of the column caps;

Fig. 4 is a side elevation of one of the brackets or members for connecting the cap plate to the column; and

Fig. 5 is a vertical section taken on line 5—5 of Fig. 4.

Referring to the drawing, the concrete construction shown therein as embodying the invention, comprises a flat slab 1 having solid panels 3 and bays 5 between the solid panels having series of transversely extending ribs 7 depending therefrom with domes or recesses 9 between said ribs distributed throughout the bays to the margins of the solid panels.

To reinforce the slab, any suitable system of reinforcing rods or members may be employed. In the present instance, crossing series of rods or members 11 are provided in the ribs 7 adjacent the lower faces thereof, and crossing series of tension reinforcing rods or members 13 may be provided in the solid panels adjacent the upper surface thereof. The system of reinforcing rods or members may be similar to the system shown in my copending application Serial No. 314,347, filed July 30, 1919, and therefore, further showing and description thereof herein are unnecessary.

As stated, in certain forms of construction it is desirable to provide columns and caps for supporting the solid panels without employing flaring capitals such as are shown in my patent referred to. These columns and their caps may be similar in construction, and therefore, a description of one will suffice for all. In the present instance of the invention, a metal column 15 is shown, H-shaped in transverse section, and having flanges 17 connected by a web 19. The column may be enclosed in concrete 21 which

may fill the spaces between the web and flanges of the column and may be square or circular in transverse section as desired. The column may project upward through 6 floors continuously from floor to floor as desired.

Next will be described the cap for the column which may be enclosed in and support the solid panel. This cap, in the 10 present instance of the invention, comprises a base plate 23 which may be formed of sections to enable lateral presentation thereof to the column without the necessity for inserting the cap over the end and along the 15 column to the position required. In the present instance, the cap comprises a pair of opposed side sections 25 adapted to engage the outer faces of the flanges 17 of the column and a pair of opposed end sections 20 27 having inner portions adapted to project in toward the web and into engagement with the inner faces of the flanges of the column. In the present exemplification of the invention, the base plate 23 is of 25 octagonal form, but obviously it may be of circular or other form as desired. To strengthen the base plate and provide means for securing the same to the column, it may be provided with a number of 30 brackets or members 29, in the present instance, of triangular shape, as will be noted in Fig. 4, each of said brackets comprising a web 31, base angles 33, side angles 35 and end angles 37 riveted or otherwise 35 secured to the web along the margins thereof. The number of said brackets 29 employed may be varied, and the location thereof may vary, but in the present instance, eight such brackets are employed 40 extending from the points of the periphery of the octagonal base in a general radial direction inward toward the column. The brackets at the juncture of the base plate sections may be extended inward along the 45 inner faces of the flanges of the column toward the web thereof, and be riveted or otherwise secured thereto.

The angle bars 33 at the lower edges of the brackets may be riveted or otherwise 50 secured to the base plate, and the end angle bars 37 of the brackets may be riveted or otherwise secured to the column. In practice, the brackets for connecting the sections of the base plate may be permanently 55 secured to the end sections 27 thereof, so that when the sections are assembled with the column, it will be merely necessary to secure the bottom angle bars 33 of the brackets to the side sections 25 of the base 60 plate, in order to connect the sections 25 and 27.

To further contribute to the secure connection of the brackets with the column, opposed angle bars 39 may be riveted or 65 otherwise secured to the under faces of the

side sections 25 and be riveted or otherwise secured to the column flanges 17 after the side sections have been presented thereto. Similarly, angle bars 41 may be riveted or otherwise secured to the under sides of the 70 end sections 27 and be riveted or otherwise secured to the column web on presentation of said end sections thereto.

The caps should be presented and secured to the columns before the concrete forming 75 the flat slab is poured. The concrete is poured onto the base plate and between the brackets to the depth required for forming the solid panel, and preferably the upper surface of the concrete will be somewhat 80 above the upper ends of the brackets, as will be noted in Fig. 2.

To protect, render fireproof and conceal the under face of the base plate, a layer of concrete 43 or other suitable material may 85 be applied thereto. The base plate may have a multiplicity of apertures 45 therein to contribute to the lightness thereof and to assist in holding the under concrete layer 43 thereof. If a metal lathing is employed 90 at the under face of the base plate, attaching devices therefor may be connected to the base plate through said apertures.

The base plate should have sufficient area 95 so that the perimeter thereof will extend a substantial distance beyond the column and furnish adequate support for the solid panel.

By the construction described, a strong and simple cap is provided for the column, the sections of which may be readily formed 100 and assembled with the column, and when the concrete is poured the cap will be enclosed in the solid panel. The term "en- 105 closed" is to be understood in the claims as sufficiently comprehensive to cover a cap which has its bottom surface exposed or covered with a protective layer of concrete 43. In some instances this protective layer of concrete might be eliminated, and the lower face of the plate protected by other 110 suitable means.

It will be understood that the invention is not limited to the specific embodiment shown, and that various deviations may be made therefrom without departing from the 115 spirit and scope of the appended claims.

What is claimed is:—

1. In concrete construction, the combination with a metal column of H-shaped cross section and a cap for said column comprising a base plate having side sections the inner edges of which fit against the paneled members of the column and end sections the inner edges of which enter between the parallel members of the column for lateral 125 presentation to the flanges and web of the column respectively, means for securing said sections together, and brackets for securing said sections to the column.

2. In concrete construction, the combina- 130

tion with a metal column, of a cap therefor adapted for enclosure in a solid concrete panel and comprising a base plate having a plurality of sections each of which is 5 formed as a flat plate adapted for lateral presentation to a portion of said column intermediate the ends thereof and separate brackets for connecting the plate sections to the column.

10 3. In concrete construction, the combination with a column, of a cap surrounding the column and formed in sections for lateral presentation to the column and attachable thereto intermediate the ends of the 15 column, said cap comprising a base plate and brackets connected to the base plate and to the column.

4. In concrete construction, the combination with a column, of a cap formed in sections for lateral presentation to the column and attachable to the column intermediate its ends, said cap comprising a base plate and brackets connected to the column and having strengthening marginal flanges connected to the base plate.

5. In concrete construction, the combination with a column, of a cap surrounding the column and attachable thereto intermediate its ends, said cap comprising a base 20 plate, webs disposed transversely to the base plate at spaced intervals, means to secure the webs to the column, and means to secure the webs to the base plate.

6. In concrete construction, the combina-

tion with a column, of a cap formed in sections for lateral presentation to the column and attachable to the column intermediate its ends, said cap comprising a base plate and brackets connected to the column and to the base plate, and under brackets secured 40 to said base plate and column.

7. In concrete construction, the combination with a column, of a cap surrounding the column and formed in sections for lateral presentation to the column and attachable thereto intermediate the ends of the column, said cap provided with a base plate having apertures therein to facilitate holding a layer of concrete or other surface material to the under side of the base plate 50 and brackets connecting the base plate and column.

8. In concrete construction, the combination with a column of sufficient length to project from one floor through another 55 floor, a cap for supporting a solid concrete panel of a recessed floor comprising sections adapted for lateral presentation to a portion of the column intermediate the ends thereof, said sections projecting a substantial distance from the column to furnish extended support for the solid panel, and triangular brackets secured to the sections and to the column intermediate the ends of the column.

In testimony whereof, I have signed my name to this specification.

EDWIN F. ALLBRIGHT.
